(57) **CLAIM**

The ornamental design for a light head, as shown and described.

DESCRIPTION

FIG. 1 is a front perspective view of a first embodiment of a light head;

FIG. 2 is a top plan view of the first embodiment of the light head;

FIG. 3 is a front side view of the first embodiment of the light head, the opposite rear view being identical;

FIG. 4 is a bottom view of the first embodiment of the light head;

FIG. 5 is a right side view of the first embodiment of the light head, the opposite left side view being identical;

FIG. 6 is a front perspective view of a second embodiment of the light head;

FIG. 7 is a top plan view of the second embodiment of the light head;

FIG. 8 is a front side view of the second embodiment of the light head, the opposite rear view being identical;

FIG. 9 is a bottom view of the second embodiment of the light head; and,

FIG. 10 is a right side view of the second embodiment of the light head, the opposite left side view being identical.

The broken lines shown in the figures represent portions of the light head that form no part of the claimed design.
